UNITED STATES PATENT OFFICE.

GEORGE G. LEWIS, OF SYCAMORE, ILLINOIS.

INSULATING APPARATUS.

SPECIFICATION forming part of Letters Patent No. 632,654, dated September 5, 1899.

Application filed September 17, 1897. Serial No. 652,029. (No model.)

To all whom it may concern:

Be it known that I, GEORGE G. LEWIS, a citizen of the United States, residing in Sycamore, in the county of De Kalb, State of Illinois, have invented certain new and useful improvements in Insulating Apparatus, of which the following is a specification.

My invention relates to apparatus for coating or recoating wires with insulating material in liquid form, and has for its object to provide an apparatus by which the insulating material may be applied to the wire uniformly on all sides expeditiously and without much labor on the part of the operator.

That which I regard as new will be set forth in the claims.

Referring to the drawings, Figure 1 is a side elevation. Fig. 2 is a plan view. Fig. 3 is a longitudinal vertical section of part of the apparatus, the remainder being in side elevation. Fig. 4 is a vertical cross-section on line 4-4 of Fig. 1. Fig. 5 is a longitudinal vertical section on line 5-5 of Fig. 2.

Stated generally, my improved apparatus consists of a reservoir for the insulating material or "paint," as it is commonly called, a conveyer-belt by which the paint is elevated from the reservoir to a point above the wire to be coated, means for transferring the paint from the conveyer to and discharging it upon the wire, and means for wiping the wire in order to smooth the paint and remove drippings. My improved apparatus also contains means for carrying back the surplus paint to the reservoir.

Referring to the drawings, 6 indicates a reservoir, which is preferably a tank mounted upon a pole 7, the pole being for the purpose of raising the apparatus to the wire 8. As shown in Fig. 4, the pole is preferably arranged at one side of the reservoir, but it may be otherwise arranged, if desired.

9 indicates a pulley which is journaled in the lower portion of the reservoir, as shown in Figs. 3 and 4.

10 indicates a second pulley, which is journaled in a suitable support 11 above the reservoir and wire. In the form of apparatus illustrated in the drawings the support 11 consists of a bar, one end of which extends upward to receive the journal 12 of the pulley 10, the lower end of said bar extending down

into the reservoir and forming a support for the journal of the lower pulley 9, thence passing up and being secured to a framework 13, 55 which carries a pole-socket 14. These details of construction, however, may be varied, and I do not wish to be restricted to mounting the parts specifically in the manner described.

15 indicates an endless belt which passes 60 around the pulleys 9 10, as shown in the drawings.

16 indicates a perforated wheel which is arranged at one side of the pulley 10 in juxtaposition thereto and is preferably mounted 65 upon the same journal 12. If desired, the pulley 10 and wheel 16 may be made integral with each other; but the wheel 16 should be of somewhat less diameter than the pulley 10, so that the paint carried by the belt 15 may 70 be scraped from said belt onto the periphery of the wheel 16.

17 indicates a scraper which is mounted over the pulley 10 and is adapted to scrape the upper surface of the belt 15. The scraper 75 17 is provided with back and end plates 18 19, respectively, and with a nose 20, arranged to discharge upon the perforated wheel 16, as shown in Figs. 2 and 5, and preferably the body of the scraper is tilted slightly toward 80 the wheel 16, so that the paint scraped from the belt 15 will readily flow onto said wheel.

21 22 23 24 indicate side and end plates which together form a funnel-shaped box or casing by which drippings are directed back 85 into the reservoir 6.

25 indicates a roller arranged at the front of the device, mounted upon a suitable journal carried by a pivoted arm 26, as shown in Figs. 2 and 3.

27 indicates the pivot of the arm 26, which is arranged about midway of the length of said arm, as shown in Fig. 3.

28 indicates a slot in the arm 26 near its end.

29 indicates a second arm pivoted on a pivot 95 30 in a manner similar to the arm 26, except that it is at the other side of the center of the device, as shown in Fig. 3, and as there shown the arms 26 29 are connected by a bolt 31, which passes through the slot 28 in the arm 26 and through a suitable hole in the arm 29. The arm 29 carries at its outer end a holder 32 for a wiper 33, said holder being arranged to hold the wiper up against the under side

of the wire. By this construction when the roller 25 is raised the wiper will also be raised. As shown in Fig. 2, the roller 25 is provided with a groove 34, and said groove is arranged in line with the wiper 33 and with the perforated wheel 16, by which arrangement when the groove in the roller 25 receives the wire to be coated the apparatus will be guided along the wire in such manner that the perforated wheel 16 will be directly over the wire and the wiper 33 directly under it. In operation as the operator moves the apparatus along there will be more or less of an upward pressure against the grooved roller 25, and consequently the wiper will be forced up against the wire, enabling it to do its work properly.

The operation of my improved apparatus is as follows: The reservoir having been filled 20 with paint the apparatus is raised to the wire by means of the pole 7, the grooved roller 25 being fitted upon the wire, upon which also rests the perforated wheel 16. In order to fully prevent lateral displacement of the apparatus, 25 the roller 25 is provided with a disk 35 at one side, and the perforated wheel 16 is provided with a similar disk 36 at the opposite side of the wire from that at which the disk 35 is placed. The pulley 10 also coacts with the disk 36 to prevent lateral displacement of the apparatus. As the apparatus moves along the frictional contact of the wire and the perforated wheel 16 will cause said wheel to rotate in the direction indicated by the arrow 30 in Fig. 1, thereby rotating the pulleys 10 and 9, and consequently operating the belt 15, which descends into the paint on one side, rising on the other with a coating of paint. As the belt passes under the scraper 17 the paint on its outer surface is scraped off and discharged through the nose 20 upon the perforated wheel 16. A part of the paint passes through the perforations in said wheel, the remainder being carried around on the outer 35 surface thereof; but all the paint discharged upon said wheel is finally delivered upon the wire in a stream, as what passes through the upper perforations in said wheel is dropped through the lower perforations to the wire. After the paint has been applied to the upper 40 surface of the wire, as above stated, it flows around to a greater or less extent to the under side thereof until the wiper 33 is reached, when the accumulated paint is spread 45 smoothly over the under surface and sides of the wire by the wiper, all superfluous paint being removed. As soon as the wiper becomes saturated with paint the surplus drips from it into a pan 37, arranged below it, and thence flows into the reservoir through openings 38, provided for that purpose, as shown in Fig. 5. 39 indicates a strainer in the pan 37 to intercept impurities.

Instead of operating my improved insulating apparatus by means of a pole from the ground a cord may be attached to it, so that it may be drawn along the wire. When the appara-

tus is used in this manner, the wiper is held up in contact with the wire by a spring 40, one end of which is connected to the arm 29 near the wiper, the other end being connected to a suitable stationary support 41, connected to the frame of the apparatus, as shown in Fig. 3, the bolt 31 under such circumstances being removed.

I have described my improved apparatus in detail, but wish it to be understood that I do not limit myself to the specific construction described, as many modifications thereof may be made without departing from the spirit of my invention. Furthermore, while I have described my invention as an insulating apparatus, I wish it to be understood that I do not wish to be restricted to using it for that purpose alone, as it may be used for any other purpose to which it is adapted; and it should be understood that it is not limited to insulating wires or to use with insulating material, as it may be used for painting other objects.

That which I claim as my invention, and desire to secure by Letters Patent, is—

1. In a painting apparatus, the combination with a reservoir carried below the object to be painted, of means automatically acting to elevate the paint and apply it in a stream to said object, substantially as described.

2. In a painting apparatus, the combination with a reservoir carried below the object to be painted, of means automatically acting to elevate the paint and discharge it in a stream upon the object to be painted, from above, substantially as described.

3. In a painting apparatus, the combination with a reservoir carried below the wire to be painted, of means automatically acting to elevate the paint and discharge it from above in a stream upon the wire, and a wiper acting on the painted wire after the paint has been discharged upon it, substantially as described.

4. In a painting apparatus, the combination with a reservoir carried below the wire to be painted, of means automatically acting to elevate the paint and discharge it from above in a stream upon the wire, a wiper acting on the painted wire after the paint has been discharged upon it, and a guide at the forward end of the apparatus, substantially as described.

5. In a painting apparatus, the combination with a reservoir adapted to contain paint, of a conveyer adapted to conduct the paint from the reservoir to the object to be painted, and means for removing the paint from said conveyer and applying it in a stream to the object to be painted, substantially as described.

6. In a painting apparatus, the combination with a reservoir, of a conveyer adapted to conduct the paint from said reservoir to the object to be painted, and a scraper for removing the paint from said conveyer and discharging it in a stream on the object to be painted, substantially as described.

7. In a painting apparatus, the combination with a reservoir, of a paint-conveyer consisting of pulleys and an endless belt carried thereby, means for operating said conveyer by the movement of the apparatus along the wire, and means for removing the paint from the belt and discharging it upon the wire, substantially as described. 5
8. In a painting apparatus, the combination with a reservoir, of a paint-conveyer consisting of pulleys and an endless belt carried thereby, means for operating said conveyer by the movement of the apparatus along the wire, and a scraper acting to scrape the paint from the surface of the belt and discharging it upon the wire, substantially as described. 10
9. In a painting apparatus, the combination with a reservoir, of a paint-conveyer adapted to carry paint from said reservoir to a point above the object to be painted, and a wheel adapted to travel on the object to be painted, said wheel being arranged to receive paint from said conveyer and to discharge it upon the object to be painted, substantially as described. 15
10. In a painting apparatus, the combination with a reservoir, of a wheel adapted to receive paint from said reservoir and to apply it in a stream to the object to be painted, substantially as described. 20
11. In a painting apparatus, the combination of a reservoir, and a perforated wheel adapted to receive paint from said reservoir and to apply it in a stream to the object to be painted, substantially as described. 25
12. In a painting apparatus, the combination with a reservoir, of a paint-conveyer consisting of pulleys and an endless belt carried thereby, means for operating said conveyer by the movement of the apparatus along the wire, a wheel connected to one of said pulleys and traveling on said wire, and means for transferring paint from said belt to said wheel, substantially as described. 30
13. In a painting apparatus, the combination with a reservoir, of a paint-conveyer consisting of pulleys and an endless belt carried thereby, means for operating said conveyer by the movement of the apparatus along the wire, a wheel connected to one of said pul- 35
- leys and traveling on said wire, means for transferring paint from said belt to said wheel, and a guide-roller arranged in advance of said wheel, substantially as described. 40
14. In a painting apparatus, the combination with a reservoir, of a paint-conveyer consisting of pulleys and an endless belt carried thereby, means for operating said conveyer by the movement of the apparatus along the wire, a wheel connected to one of said pulleys and traveling on said wire, means for transferring paint from said belt to said wheel, a guide-roller arranged in advance of said wheel, and a wiper behind said wheel, substantially as described. 45 55
15. In a painting apparatus, the combination of pivotally-supported arms 26 29, said arms being loosely connected together, a guide-roller carried by one of said arms, a wiper carried by the other of said arms, said guide-roller and wiper being arranged at opposite sides of the wire, and means for applying paint to the wire between said guide-roller and wiper, substantially as described. 60 70
16. In a painting apparatus, the combination with suitable supporting devices, of a guide-roller arranged at the forward end of the apparatus, a wiper at the rear end of the apparatus, means for applying paint to the wire between said guide-roller and wiper, and means for automatically applying said wiper to the wire when said guide-roller is moved in an upward direction, substantially as described. 75 80
17. In a painting apparatus, the combination with a reservoir, of a paint-conveyer, and a scraper adapted to scrape the paint from said conveyer upon the wire, substantially as described. 85
18. A wire-insulating apparatus consisting of a liquid-reservoir arranged below the wire, means supporting said reservoir from the wire, and means for applying liquid from said reservoir in a stream to the wire to be coated, substantially as described. 90
